ANKER PETERSEN, OF WINTHROP, MASSACHUSETTS, ASSIGNOR TO AMERICAN WIRE-MOLD COMPANY, OF HARTFORD, CONNECTICUT, A CORPORATION OF CONNECTICUT.

STRAND-GUIDE FOR BRAIDING-MACHINES.

1,386,071.

Specification of Letters Patent.

Patented Aug. 2, 1921.

Application filed July 30, 1920. Serial No. 400,171.

To all whom it may concern:

Be it known that I, ANKER PETERSEN, a citizen of the United States of America, and resident of Winthrop, in the county of 5 Suffolk and State of Massachusetts, have invented new and useful Improvements in Strand-Guides for Braiding-Machines, of which the following is a specification.

This invention relates to improvements 10 in braiding machines and particularly to that type in which two series of thread carriers are revolved in relatively opposite directions one within the other and in which strand carrier levers are employed for guiding the 15 strands of the outer series alternately above and below the carriers of the inner series. Such a mechanism is disclosed in the patent to Petersen 1,105,452, July 28, 1914. In said patent the strand carrying lever comprises 20 a substantially rigid frame provided at its free extremity with a thread guide over which the thread passes on its way to the braiding point. In passing to the braiding point the thread passes between the driven 25 roll of the thread carrier and the two driving rolls by which the thread carrier is actuated, such an arrangement of rolls being clearly indicated in Figure 3 of the patent referred to. As the thread passes between said 30 rolls it is caused to move to a certain extent above and below its normal position as determined by the braiding point and the position of the strand carrying lever at that instant. As the strand at this time is under 35 tension, such movement tends to rupture the thread if the latter be weak or of small size, the relatively rigid strand carrier resisting any movement of the thread such as would provide slack at this time.

40 An object of this invention is to provide a strand carrier of such construction that when the thread is subjected to unusual strain, such as above pointed out, it may be slackened slightly to avoid breakage of the 45 same. To this end in accordance with the present invention it is proposed to provide a strand carrier having the thread guiding portion thereof of sufficiently flexible construction to permit it to give slightly upon 50 undue tension in the strand, whereby to prevent breakage of the latter.

In machines of the above character it is desired that the strand carriers occupy as little space as possible in order to keep down 55 the diameter of the rotating machine parts,

and it is furthermore desirable that such strand carriers be accurately moved and without any looseness or back-lash in their oscillation.

A further object of the invention is to 60 provide strand carriers of a form such that they may be nested closely between the rotary frame and the cam cylinder whereby they are actuated, and furthermore to provide a cam of such form that the carriers 65 may be accurately moved throughout the extent of their swing. To this end it is sufficient to provide strand carriers of curved form which when in horizontal position shall lie substantially parallel to the cam cylinder 70 and the rotating frame within the same, and to provide a cam slot, the depth of which shall vary in accordance with the path of movement of the cam follower carried by the strand carrying lever throughout the path 75 of movement of the same.

One mode of carrying into effect the above objects has been illustrated in the accompanying drawings in which—

Fig. 1 is a plan view of such portion of 80 a braiding machine of the class described as serves to illustrate the application thereto of a strand carrying lever of the form forming the subject matter of this invention;

Fig. 2 is an elevation from the inside of 85 the cam cylinder shown in Fig. 1, the pivot pin for the strand carrier being shown in section;

Fig. 3 is a radial cross section through the 90 rotating frame and the cam cylinder and through the axis of the cam follower mounted upon the strand carrier;

Fig. 4 is a diagrammatic cross-section 95 through the cam cylinder taken at the lowermost point of the cam groove therein and illustrating the variation in depth of the cam groove at different points in the same;

Fig. 5 is a diagrammatic view illustrating the means for driving a braiding carrier 100 of the inner series and showing the limits of deflection of the outer thread as it passes between the drive rolls.

1 is the rotating frame upon which the outer set of strand carriers are mounted, and 105 2 is the relatively fixed cam cylinder surrounding said frame, said cam cylinder being provided with a cam groove 3. 4 is a bracket secured to the outer wall of the frame 1 by means of screws 5, or in any 110

other suitable manner, said bracket having a radially extending portion 6 to the outer face of which is pivoted, by means of a radially extending screw 7, a strand carrying lever 8. As will be noted from inspection of Fig. 1, this strand lever, when in the position there shown, extends throughout its length substantially parallel to the inner wall of the cam cylinder 2 and to the outer wall of the frame member 1, and thus occupies little space between said elements.

The lever member 8 is of relatively rigid construction and at its outer end is bifurcated to form a pair of opposed arms 9—10. Secured in the respective arms in any desired manner, as by means of socket openings formed in said arms, are legs 11—12 of a wire extension of hair-pin like form, said extension being of substantial length as compared with the length of the member 8 and having at its closed outer extremity a thread guiding portion 13. This wire extension is of resilient material, preferably spring steel wire, and is thus adapted to yield in a radial direction upon abnormal strain upon the strand passing thereover.

At the point 14 is provided a cam follower 15, said follower being provided with upper and lower curved surfaces 16—17 respectively, and with flat ends, such follower being in general of lenticular outline. The cam follower as thus constructed is found to be very desirable as it gives larger wearing surfaces than does a roll and there is less likelihood of the parts becoming loose in use. As will be clear from inspection of Figs. 1 and 3, the curved form of the strand carrying lever 8 together with the radial pivoting of the same causes the cam follower 15 to move in an arcuate path about a center lying in the horizontal plane of said pivot. The depth of such a groove if uniform would necessarily be so determined as to accommodate the cam follower in passing through the horizontal plane of the pivot. Such depth is, however, unnecessary at other parts of the travel of the follower and to secure the best results and to provide a close fit of the parts throughout the entire travel of the cam follower the inner walls of the cam groove are formed on a curve corresponding to the path in space of the cam follower. As illustrated in Fig. 4, this groove will be of greatest depth at the portions 18 at which the groove crosses the horizontal plane passing through the pivot 7, and will be of least depth at points 19—20, for example wherein the cam groove is most remote from said plane. With this arrangement the cam follower may be fully seated within the groove throughout its entire course of travel and any looseness or backlash between the interengaging parts is to a very large extent obviated.

In Fig. 5 the distance between lines $x-y$

indicate diagrammatically the amount which the thread is caused to deflect out of a straight line as it passes over the rolls $a-b$ and under roll c . Such deflection, if the thread is held under rigid tension, must either break or stretch the thread, either of which is disastrous to the proper operation of the machine. As above pointed out the strand guide constructed as herein shown with a flexible end serves to avoid such stretching or breaking of the yarn in a highly satisfactory manner.

I claim:

1. A braiding machine comprising a composite thread lever having rigid and flexible portions, the flexible portion being of substantial length as compared with the rigid portion and extending beyond the free extremity of the latter, said flexible portion having a thread guide adjacent its extremity, pivotal means engaging the rigid portion of the lever, and a cam follower adjacent one end of said rigid portion.

2. In a braiding machine, a thread lever comprising an elongated, relatively rigid supporting element pivotally supported adjacent one extremity, and a flexible extension of hair-pin form having its legs secured to said element adjacent its free extremity.

3. In combination in a braiding machine, a thread lever comprising a pivotally supported, relatively rigid member, said member being bifurcated at its free extremity to provide spaced arms, and a flexible extension of hair-pin form having its legs secured to said respective arms and provided with a thread guide at its closed extremity.

4. In a braiding machine, in combination, a cam carrier having a cam groove therein, and a cam follower movable along said groove, said groove having elements of one of its walls curved in directions substantially at right angles to each other.

5. In a braiding machine, a cylindrical cam carrier, a cam groove therein, and a cam follower movable along said groove, said groove having one of its walls curved in directions both axial and radial of said cylinder.

6. In a braiding machine in combination, a cylindrical cam carrier having a cam groove in its circumferential surface, and a cam follower movable along said groove, said groove varying in depth in a radial direction at successive portions of its length.

7. In a braiding machine in combination, a cam cylinder having a cam groove in its inner circumferential wall, a cam follower movable in said groove, said groove having portions thereof lying adjacent the upper and lower bases of said cylinder, said groove being of less axial depth at said portions than at those parts thereof intermediate said portions.

8. In a braiding machine, in combination,

- a cam cylinder having a continuous cam groove therein provided with upper and lower portions, a cam follower, a pivoted lever supporting said follower, and a radially extending pivot pin for said lever, said pin being fixed in a plane substantially midway between said upper and lower portions of the groove, the inner wall of said groove being curved from point to point in its length about a center located in said plane.
9. In a braiding machine, in combination, a cam cylinder provided with an internal cam groove having upper and lower portions and intermediate connecting portions, a curved lever member pivoted to swing about an axis lying in a plane intersecting said intermediate portions, a cam follower mounted adjacent the free extremity of said lever member, said cam groove being deeper at its upper and lower portions whereby to accommodate the cam follower in its oscillation about its pivotal support.
10. In a braiding machine of the class described, in combination a cam cylinder pro-
- vided with a cam groove upon its inner wall, a lever member mounted to swing inside said cylinder about a substantially radial pivot and a cam follower pivotally mounted upon said lever member and engaging within said groove, said lever member, at one position of its arc of oscillation extending substantially concentric with the inner surface of the cylinder.
11. In a braiding machine of the class described, in combination a cam cylinder having a cam groove in its inner wall, a lever member pivoted to swing about a substantially radial pivot said pivot lying in a plane intersecting said cylinder intermediate its bases, and a cam follower mounted on said lever member, said lever member being so curved that when its axis lies in said plane the lever member is substantially concentric with the inner wall of said cylinder.

Signed by me at Boston, Massachusetts, this 26th day of July, 1920.

ANKER PETERSEN.
